UNITED STATES PATENT OFFICE.

HENRY F. CLARK, OF POUGHKEEPSIE, NEW YORK.

CARTRIDGE.

No. 819,518.

Specification of Letters Patent.

Patented May 1, 1906.

Application filed July 15, 1905. Serial No. 269,786.

To all whom it may concern:

Be it known that I, HENRY F. CLARK, a citizen of the United States, residing at Poughkeepsie, in the county of Dutchess and State of New York, have invented an Improvement in Cartridges, of which the following is a specification.

Heretofore in the manufacture of cartridges for breech-loading firearms numerous constructions have been devised in attempts to lubricate a jacketed bullet, and so far as I am aware none of them has been successful practically; and the object of my present invention is to effect this result—that is to say, to lubricate a metal-jacketed bullet.

In carrying out my invention I employ, together with a shell and suitable cap, a bullet having a shoulder near its base adapted to fit within the reduced open end of the shell, providing an annular space surrounding the bullet and between the same and the reduced end of the shell, which annular space is filled with a suitable lubricant, and the edge of the shell is then crimped or turned down into contact with the surface of the bullet, thereby providing a closed chamber or compartment for holding the said lubricating material unexposed to external or atmospheric influences.

30 In the drawings, Figure 1 is an elevation of a cartridge embodying my improvement. Fig. 2 is a central longitudinal section of the same; and Fig. 3 is a section on line x x , Fig. 2.

35 a designates a shell provided at its closed end with a cap 2 , and at the opposite end there is a reduced portion b .

c is a bullet having a slightly-enlarged base d , adapted to fit appreciably within the reduced end b of the shell, the base d providing a shoulder 3 , and after the bullet is inserted in the shell the desired distance an annular space is produced between that portion of the bullet adjacent to the shoulder 3 and that portion of the reduced end b which extends beyond said shoulder 3 . This annular space I fill with a suitable lubricant 4—such, for instance, as tallow—and the edge 5 of the reduced portion of the shell b is preferably crimped or rolled in tightly against the surface of the bullet, thereby inclosing the lu-

bricant in an annular compartment whose walls are the surface of the bullet and the reduced end portion b of the shell and whose ends are the shoulder 3 and the inturned end 55 of the said reduced portion of the shell.

It will be apparent that with this structure not only is the lubricant protected from all external agencies, but also the powder is protected from the lubricant and all other moisture, and in experimenting with this improved structure I have found the bullet and barrel to be evenly lubricated, with a resultant reduction of friction and heating and consequent increased efficiency of the fire- 65 arm.

I claim as my invention—

1. A cartridge for small-arms, comprising a shell having a reduced end portion, a bullet having a slightly-enlarged base adapted to fit 70 appreciably within the reduced end of said shell, and a lubricating material filling the annular space between the bullet and reduced end of the shell, and the shoulder formed by the enlarged end of the bullet. 75

2. A cartridge, comprising a shell having a reduced end portion, a bullet having a slightly-enlarged base adapted to fit appreciably within the reduced end of said shell and a lubricating material filling the annular 80 space between the bullet and reduced end of the shell and the shoulder formed by the enlarged end of the bullet, the edge of said reduced end being rolled down on the surface of the bullet to form a chamber in which said 85 lubricating material is inclosed.

3. A cartridge for small-arms comprising a shell having a reduced end portion, a bullet having a slightly-enlarged base adapted to fit appreciably within the reduced end of said 90 shell, and the free edge of the reduced portion contacting with the bullet, and a lubricating material filling the annular space between the bullet and the reduced end of the shell and the shoulder formed by the enlarged 95 end of the bullet.

Signed by me this 6th day of July, 1905.

HENRY F. CLARK.
